UNITED STATES PATENT OFFICE.

LOUIS ARONS, OF CHICAGO, ILLINOIS.

TROUSERS-SUPPORTER.

1,263,729.

Specification of Letters Patent. Patented Apr. 23, 1918.

Application filed October 11, 1916. Serial No. 124,945.

To all whom it may concern:

Be it known that I, LOUIS ARONS, a citizen of the United States, residing at Chicago, Cook county, State of Illinois, have invented 5 certain new and useful Improvements in Trousers-Supporters, of which the following, taken in connection with the drawings, is a description.

The primary object of my invention is to 10 provide a garment supporter of the class designed to be worn inside the waist band of a garment for the purpose of holding the garment in proper position, preventing the same from sagging or wrinkling at the waist 15 line and to give a better shape in outward appearance to the garment itself.

A further object of my invention is to 20 provide such a supporter to be used particularly with men's trousers, such supporter having a belt provided with upwardly extending stays or supports having attaching devices adapted to be engaged with buttons or other fastenings secured to the garment and thereby maintain the same in proper 25 position.

A further object of the invention is to 30 provide such a supporter which is designed to fit snugly around the body of the wearer outside of the shirt, waist, or other garment, thereby holding the same in proper position, at the same time supporting the trousers or other garment in place without the use of suspenders at the outer belt, as is customary.

35 In the accompanying drawings, I have illustrated what I now consider the preferred form of my invention, although in the practical embodiment of the same I contemplate its use with other garments and with a 40 greater or lesser number of supporting members suited to the purpose for which it is to be used. In these drawings,

Figure 1 is a perspective view of the 45 waist band of a pair of trousers having my supporter arranged in place in connection with the same;

Fig. 2 is an enlarged detail of the belt and one of the supporting members, a portion being broken away to show the construction;

Fig. 3 is an enlarged vertical, sectional detail of the supporter and the waist band to which it is attached.

For the purpose of illustration, in carrying out my invention, A represents the

upper body portion of a pair of trousers provided with buttons *a* attached to the inside of the waist band of the trousers in the proper position for attaching suspenders, if suspenders were being worn.

60 A belt *B* is provided of any suitable material, preferably fabric, having attached at each end thereof a fastening means such as a buckle *b*, shown in Fig. 1.

Attached to this belt and extending upwardly therefrom are a plurality of stays or braces *C*, preferably formed of thin, non-rustable metal, having one end thereof *c* bent upon itself to form a loop extending transversely across the end of the stay. 70 Suitably engaged within this loop by passing therethrough is one side of a wire fastener *C'* preferably formed in the shape shown in Fig. 2, having one straight side forming a hinging engagement with the loop *c* of the stay, and one curved side *c'*. When in use one of the buttons *a* of the garment is passed through this fastener *C'*, the curve *c'* of the fastener taking over the button engaging means and holding the same in 80 proper position.

A casing *D*, preferably of fabric, incloses the stay *C*, and is secured by stitching or otherwise directly to the belt *B*.

85 A plurality of these upwardly extending stays are provided with each belt and arranged wherever desired to make the proper engagement with the fastening devices on the garment with which the supporter is to be worn. To adjust the same, the wire 90 fastener *C'* on the free end of each stay is removably attached to the button *a* on the garment with the curve *c'* on the wire fastener pointing downward on the inside of the garment band. The buckle is then adjusted to fit the body of the wearer and the 95 device is ready to use, it being necessary simply to engage and disengage the buckle *b* when the garment is to be worn.

100 It will be observed that the supporter may be easily and quickly removed from the garment by simply disengaging each wire fastening *C'* from the button on the garment to remove the same when desired, no stitching or other permanent fastenings being 105 utilized between the supporter and the garment with which it is used.

I claim:

110 1. A garment supporter comprising a belt, a plurality of upwardly-extending stay

members secured to said belt, and a rigid attaching member hingedly secured to each of said stay members, substantially as described.

5 2. A garment supporter comprising a belt of flexible material, a plurality of upwardly extending stay members secured to

said belt, a casing inclosing each of said stay members, and a rigid attaching device pivotally secured to the free end of each stay ¹⁰ member, substantially as described.

In testimony whereof I have signed this specification.

LOUIS ARONS.
